4 Claims. (Cl. 176—2)

Our invention relates to the manufacture of vacuum electric incandescent lamps, particularly to lamps of the elongated tubular type commercially known as the "lumiline" lamp wherein the filament extends along the greater part of the length of a tubular envelope whose length is many times its diameter. More particularly, our invention relates to the gettering of such lamps.

It is well known that lamps of the so-called "lumiline" type are difficult to clean-up by the usual process of providing a phosphorus getter in the neighborhood of the filament and running the lamp on an overload after it is sealed off from the exhausting pump. The reason is probably that, owing to charges on the envelope, it is difficult to develop the discharge between the ends of the filament on which this process is known to depend. Nor is it possible to obtain a satisfactory clean-up by passing a high-frequency discharge through the residual gas, for example by a Tesla coil.

We have found that it is possible to obtain a satisfactory clean-up by providing the lamp with an external electrode and applying between this electrode and the filament (preferably heated to its normal operating temperature) an impulsive voltage, so as to cause to pass through the residual gas a plurality of intermittent discharges separated by intervals long compared with the duration of each. The explanation of this fact does not, of course, form part of the invention; but it seems likely that, in accordance with the prevalent theory of gettering, the impulsive discharges form a surface adapted to absorb the gas and that the interval between them is necessary in order that the gas may diffuse to this surface to be absorbed there before it is subjected to a later discharge.

One object of our invention is to provide an improved method for cleaning up the residual gases in electric incandescent lamps of the vacuum type.

An important feature of our invention is the application of an impulsive voltage between the lamp filament and an external electrode so as to produce a plurality of intermittent discharges through the residual gas within the lamp envelope, the successive discharges being separated by intervals appreciably long as compared to the duration of each discharge.

Further objects and advantages of our invention will appear from the following description of a species thereof.

The drawing is a diagrammatic view of appa-

ratus which may be employed in practicing our invention.

According to the invention, the manufacture of a lamp of the type specified comprises the steps of providing within the envelope a suitable getter, exhausting the lamp, providing the lamp with an external electrode and applying between the said external electrode and an internal electrode (preferably the filament and preferably while the latter is heated to its normal operating temperature) an impulsive voltage, the duration of each pulse being less than the interval between successive pulses. The lamp is preferably sealed off before the impulsive voltage is applied, but if desired, the sealing off operation may be postponed, in known manner, until after the clean-up or gettering operation is completed.

The external electrode may, of course, be merely temporary, and be removed after the clean-up is complete. Thus it may be a wire wrapped in a helix around the lamp envelope, or a split metal tube into which the lamp envelope is inserted. It need not surround the envelope completely; thus it may be an elongated plate extending along the entire length of the envelope and curved so as to make contact with about one-third of the circumference of the envelope.

The impulsive voltage may be generated by any known means. If it is generated by 50-cycle current, there are preferably not more than two or three pulses per half cycle. The peak value of the impulsive voltage is preferably higher than the greatest overload that could be safely applied to the filament in the usual gettering process. Thus, if the lamp is designed for 250 volts, the peak of the pulse should be 400-600 volts. The discharges produced by the impulsive voltage should be visibly luminous in suitably darkened surroundings.

In one embodiment of the invention, described by way of example, the envelope 10 is 220 mm. long and 25 mm. in diameter. The filament spiral 11 is 205 mm. long and is designed to operate on 250 volts. Before the filament is mounted in the envelope, it is provided in the usual manner with a phosphorus getter. After the lamp is exhausted, it is sealed off. A wire 12 is wrapped in a helix of some ten turns about the envelope. The secondary 13 of a step-up iron-cored transformer 14 with 100/9000 turns is connected between the said wire 12 and the filament 11 by conductors 15 and 16; the primary 17 is fed from 250 A. C. mains terminals 18—19 through a resistance 19 of 2500 ohms in series with a capacity

20 of 0.5 mfd., a bee-hive argon filled glow lamp 21 being connected in parallel with the capacity and the primary. The filament 11 is heated by being connected directly to the 250 A. C. means 18—18 by conductors 22, 23. The resistance 19 and capacity 20 and the striking voltage of the glow lamp 21 are adjusted so that one pulse of voltage is generated in the transformer 14 per half-cycle of the supply current.

While we have found the method described hereinabove to be particularly useful in connection with the manufacture of tubular incandescent lamps of the "lumiline" type, it has also been found to be advantageous in the manufacture of various other types of vacuum electric incandescent lamps, particularly lamps of the low-voltage type operating on less than 110 volts.

What we claim as new and desire to secure by Letters Patent of the United States is:

1. A method of cleaning up the residual gases in a vacuum electric incandescent lamp having a filament mounted within an envelope containing a quantity of getter material, which comprises adjusting an external electrode into close proximity to said envelope, and applying an impulsive voltage between said external electrode and said filament to thereby produce a plurality of intermittent discharges therebetween, the duration of each voltage impulse being appreciably less than the interval between successive impulses.

2. A method of cleaning up the residual gases in a vacuum electric incandescent lamp having a filament mounted within an envelope containing a quantity of getter material, which comprises adjusting an external electrode into close

proximity to said envelope, heating said filament to its normal operating temperature by passage of current therethrough, and applying an impulsive voltage between said external electrode and said filament to thereby produce a plurality of intermittent discharges therebetween, the duration of each voltage impulse being appreciably less than the interval between successive impulses.

3. A method of manufacturing vacuum electric incandescent lamps which comprises mounting a filament within an envelope, inserting a quantity of getter material within said envelope, exhausting and sealing off said envelope, adjusting an external electrode into close proximity to said envelope, and applying an impulsive voltage between said external electrode and said filament to thereby produce a plurality of intermittent discharges therebetween, the duration of each voltage impulse being appreciably less than the interval between successive impulses.

4. A method of manufacturing vacuum electric incandescent lamps which comprises mounting a filament within an envelope, inserting a quantity of getter material within said envelope, connecting said envelope to a vacuum pump and exhausting said envelope, adjusting an external electrode into close proximity to said envelope, applying an impulsive voltage between said external electrode and said filament to thereby produce a plurality of intermittent discharges therebetween, the duration of each voltage impulse being appreciably less than the interval between successive impulses and sealing off said envelope.
